UNITED STATES PATENT OFFICE.

ETHEL ZOLLER, OF LANSING, MICHIGAN.

CHURN.

1,101,773.

Specification of Letters Patent. Patented June 30, 1914.

Application filed January 16, 1914. Serial No. 812,481.

To all whom it may concern:

Be it known that I, ETHEL ZOLLER, a citizen of the United States, and a resident of Lansing, in the county of Ingham and State 5 of Michigan, have invented certain new and useful Improvements in Churns, of which the following is a specification, reference being had to the accompanying drawings.

This invention has relation to certain new 10 and useful improvements in churns, and comprises a means for rocking the churn end-wise.

The primary object of my invention is to provide a simply constructed readily operated platform arranged to receive a churn, the construction being such that a rocking movement may be imparted to the churn 15 in actuating two pedals.

A further object of my invention is to 20 provide a platform with a base forming member, and securing said base forming member to a platform by means of suitable springs, which will permit the rocking of the base member, but will hold the base 25 member against lateral displacement.

With these and other objects in view, the present invention consists in the combination and arrangement of parts as will be herein-after more fully described and finally 30 pointed out in the appended claim it being further understood that changes in the specific structure shown and described may be made within the scope of the claim without departing from the spirit of the invention.

In the accompanying drawings forming 35 a part of this specification and in which numerals of reference indicate similar parts in the several views: Figure 1, shows a side elevational view of a churn operating member, embodying my invention. Fig. 2, is a 40 central sectional view of the same. Fig. 3, is a transverse sectional view through the same. Fig. 4, shows a perspective view of the base forming member secured to the 45 platform.

In my present invention I provide a churn operating mechanism, which can be actuated by the operator's feet, so that the hands are free to be employed in other 50 labors, if desired.

In the accompanying drawings, Fig. 1, shows a platform 1, which is square and flat, and is provided with the length-wise 55 running cleats 2. Near each corner the platform is provided with the standards 3, 3. Held upon this platform is a base

forming member 4, having the side battens 5, 5, and the end battens 6, 6, an escape opening 7 being formed within one of the battens as shown in Fig. 4. Secured to opposite edges of this base forming member are the rockers 8, 8, these rockers being secured in parallel spaced relation. As shown in Figs. 1 and 2, these rockers are of a length slightly longer than the length of the 60 platform 1.

In order to yieldingly secure the base forming member 4, to the platform 1, I employ two similar coil springs 9, 9, which have one end secured to the platform 1, and 70 the opposite end to the base forming member 4, as shown in Figs. 2 and 3. As disclosed in Fig. 3, these springs 9, contact with the sides of the rockers 8, and serve as stops preventing the rockers moving side-wise off 75 of the platform. Secured near one end of the platform 1, is a coil spring 10, which has its upper end secured to the end of the base forming member 4, as shown in Fig. 2.

Extending from the batten 6, at the end 80 opposite the spring 10, are the two similar eyes 12, and secured to each eye 12, is a bar 13, which has its lower end pivotally connected to a pedal 14, each pedal in turn being pivotally secured to an eye 15. In 85 imparting a rocking movement to the pedals 14, a rocking movement is imparted to the churn carrying base member 4, and while this member is permitted a rocking movement, the same can not work laterally 90 off of the platform owing to the stop springs 9. The spring 10, returns the rocking member 4. Held upon this base forming member 4, is the churn 16, having the lid 17, which lid is provided with the handle 18. This churn upon the inside is provided with the grating or agitating frame 20, so that as the cream flows from end to end within the rocking churn, which is 95 removably held upon the base forming member 4, the cream is properly churned.

The churn can be readily removed from the rocking member and a dish or clothes washing machine may be substituted.

My invention may be operated by a 105 woman conveniently seated within a chair, who is permitted to use her hands in knitting or in some other occupation. The device is further simple and inexpensive in construction, and both durable and efficient 110 in operation.

Having thus described my said invention,

what I claim as new and desire to secure by U. S. Letters Patent is:—

In combination, a flat square forming member, two rockers secured in parallel spaced relation to opposite edges of said base member, a platform, said rockers held upon said platform, two coil springs each having one end secured to said base and the other end to said platform, said springs acting as stops limiting the side-wise movement of said rockers, a coil spring having one end secured centrally to one end of said

base member and the other end to said platform, two ears, a pedal secured to each ear, two eyes secured to the end of said base member opposite said last mentioned spring, and two rods connecting said rods to said eyes, as and in the manner shown.

In testimony whereof I affix my signature, in the presence of two witnesses.

ETHEL ZOLLER.

Witnesses:

JOHN S. DECAMP,
CARL H. MOELTER.
